EARTH BORING APPARATUS

Edward A. Smith, Chatham, N. J., assignor to
 Raymond Concrete Pile Company, New York,
 N. Y., a corporation of New Jersey

Application February 17, 1933, Serial No. 657,156

4 Claims. (Cl. 255—19).

This invention pertains to earth boring apparatus of the type in which the drilling tool is supported on the boom of a crane. In machines of that kind the operating head room above ground level is limited by the height of the outer end of the boom. That fact has served to limit the use of machines of this type to the drilling of post holes and shallow work of like nature.

In one form of crane-supported drill, the torque generator comprises an electric motor mounted on the upper end of the drill shaft and geared thereto, the torque reaction being taken by a bar, usually telescopic, connected to the crane.

The present invention discloses improvements whereby the depth-limiting drawbacks of the above apparatus are removed by use of telescopic kellys. In one modification the kelly is placed between the motor and the cutting tool and so arranged as to permit utilization of the weight 20 of kelly, motor and gearing as a feed-load on the tool. In this apparatus the motor remains above ground level, the kelly transmits torque from motor to tool, and the torque reaction is taken by a telescopic member interconnecting motor 25 and crane.

In another modification, motor and gearing are connected to the drill by a short torque-transmitting shaft, while the torque reaction is taken by a kelly interconnecting the top of the motor 30 and the head of the boom. In this arrangement the motor follows the drill down into the hole and, as before, the weight of motor, gearing and kelly are available as a drill-load.

Further and other objects and advantages will 35 be apparent from the specification and claims, and from the accompanying drawings, which illustrate what are now considered preferred embodiments of the invention.

In the drawings:

Fig. 1 shows a form of the invention in which 40 the motor is above ground level, and the drill, deep in the hole, is driven by the motor through a telescopic rotary drive shaft or kelly.

Fig. 2 is an enlarged cross-section of the upper 45 part of Fig. 1, showing details of the arrangement of motor, gearing, kelly, etc.

Fig. 3 is an enlarged cross-section of the lower 50 part of Fig. 1, showing details of drill, lower end of kelly, etc.

Fig. 4 shows a form of the invention in which 55 the motor is below ground level.

Fig. 5 is an enlarged cross-section of part of Fig. 4, showing details of the arrangement of motor, gearing, kelly, etc.

Referring to Figs. 1, 2 and 3, numeral 10 designates the crane, mounted on creepers 12, and provided with a boom 14 hinged on the crane at 16 and adjustable in position by cable 18 passing around hoisting drum 20. Motor 22 is supported by the boom through the instrumentality of cable 24 attached to eye 26 on the motor housing, and passing over sheave 28 to drum 30 on the crane. Cable 32 leads from drum 34 over sheave 36, and down through the hollow shaft of the motor to the lower end of the kelly, as will be more fully described.

The motor is shown somewhat conventionally in the drawings, the lower end of its hollow shaft 38 having fast thereon a pinion 40 which drives gear 42 mounted for rotation on vertical shaft 44. Fast to the hub of gear 42 is a pinion 46 which drives gear 48, fast on the top of the upper kelly section 50. The above described transmission gearing is enclosed in a housing 52, upon the top of which is mounted motor 22. The lower 75 part of housing 52 is in the form of a sleeve 54 surrounding the upper part of kelly section 50. The kelly section is free to rotate in sleeve 54 but is constrained against vertical movement relative thereto, as will be apparent in Fig. 2. 80 While the apparatus is in operation the torque reaction is carried to the crane through a telescopic member 56, pivotally connected at one end to the crane at 16 and at the other end to transmission housing 52 at 58.

Current is supplied to the motor through cable 60 and is under control of the operator on the crane by means of controller lever 62.

The kelly is of the type shown in Patent No. 1,895,901, issued January 31, 1933, to H. R. Smith. 90 The lower end of each kelly section has internal keys 64 adapted to rotate the next lower kelly section by contact with splines 66 extending lengthwise of the lower section. Splines 66 are provided with notches into which keys 64 may 95 enter while the parts are in driving relationship, the notches providing shoulders such as 68 (Fig. 2) whereby the weight of the kelly, motor, and other parts mounted thereon may be effective 100 as a feed-load on the drill or boring tool, which is attached to the bottom of the lowest kelly section. The drawings show only two kelly sections, but more sections may be used if desired.

The boring tool 70 is secured by keys 72 to the 105 bottom of the lowest kelly section 74 (Fig. 3). Cable 32 engages the section 74 through ball-bearing swivel 76. It will be appreciated that by adjusting the tension in cable 32 the operator may permit any desired portion of the weight of 110

kelly, motor, and attached parts to rest on the drill.

In operation, after the drill has penetrated to the desired depth it is raised to the surface by 5 means of lines 24 and 32, its load is discharged, and it is lowered into the hole again to resume digging.

In the modification shown in Figs. 4 and 5, the bifurcated upper end of the upper kelly section 78 is attached to the free end of boom 14 10 by pin 80. The lower end of section 78 is provided with internal keys 82 to contact with external splines 84 in the next lower kelly section 86, so that section 86 can telescope into section 15 78 while maintaining their torque-resisting relationship. The lower end of kelly section 86 is fitted with internal keys 88 (Fig. 5) to engage the notched spline 90 of the lowest kelly section 92, which is attached by key 94 to the upper end 20 of motor 96 (Fig. 5).

Vertical motor shaft 98 has on its lower end a pinion 100 which, through internal gear 102, pinion 104, and internal gear 106, drives drill 70 by means of shaft 108, to the upper end of which 25 gear 106 is keyed. The above transmission gearing is enclosed by housing 110 bolted to the under side of the motor.

Current is supplied to the motor by cable 112 30 passing down through the kelly. Hoisting line 114 is attached to the upper end of the lowest kelly section, as indicated in Fig. 5 and passes over a head sheave on the boom to a drum on the crane.

In operation of the modification just described 35 the kelly does not rotate but transmits the torque reaction to the boom of the crane. The weight of the motor, transmission, and all kelly sections except the upper one is available as a drill load.

The drill or bucket may be raised to discharge 40 position by telescoping the kelly with line 114, and raising the boom with line 18.

A hole of unusual depth may be drilled by withdrawing pin 80 to disconnect the kelly from the boom, lowering kelly section 78 until its upper 45 end is at ground level, and then taking the torque reaction on bars inserted through slots 116 in the upper end of the kelly, to engage stakes driven into the ground.

It is to be understood that the invention is

not limited to the specific embodiment herein illustrated and described, but may be used in other ways without departure from its spirit as defined by the following claims.

1. In apparatus of the class described, in combination, a rotatable tool for digging a hole in the ground, a vertical telescopic drive kelly for rotating said tool, torque generating means mounted above said kelly, and means for interconnecting the sections of said kelly and said torque generator whereby while said tool is digging, the weight of said torque generator may be transmitted downwardly through said kelly to serve as a feed-load on said tool. 80

2. In apparatus of the class described, in combination, a rotatable tool for digging a hole in the ground, a vertical telescopic drive kelly for rotating said tool, a drive motor mounted above said kelly, said motor having a hollow shaft axially aligned with said kelly, and a hoisting cable attached internally to the lowest section of said kelly and passing upwardly through said hollow shaft whereby said sections may be telescoped at the will of the operator. 90

3. In apparatus of the class described, in combination, a rotatable tool for digging a hole in the ground, a vertical telescopic drive kelly for rotating said tool, a tubular drive member surrounding the upper section of said kelly, torque generating means mounted on said member, and means for interconnecting said member and the sections of said kelly whereby the weight of said generator may be transmitted downwardly through said kelly to serve as a feed-load on said tool. 100

4. In apparatus of the class described, in combination, a rotatable tool for digging a hole in the ground, a vertical telescopic drive kelly for rotating said tool, a tubular drive member surrounding the upper section of said kelly and vertically adjustable relatively thereto, a torque generator mounted on said member, and means for interlocking the kelly sections and said member whereby the weight of said member and said generator may be transmitted downwardly through said kelly to serve as a feed-load on said tool. 115

EDWARD A. SMITH.
